MULTIPLE POWER APPLICATION DEVICE

Rollin E. Campbell, Anderson, Ind.

Application April 4, 1944, Serial No. 529,531

6 Claims. (Cl. 60—97)

1

This invention relates to a multiple power application device suitable for many purposes. One of such is in moving in the pressing art, see patent No. 1,890,341, the movable head toward the buck and then applying pressing pressure therebetween which last mentioned pressure is then increased.

Since this invention is capable of use in many fields of activity, no specific application is illustrated herein, but for purposes of understanding this invention, it is to be understood same includes two relatively movable members, same being normally constrained to one position and pressure movable to another position, see said patent aforesaid.

The chief object of this invention is to provide a pressure operable power device capable of functioning as aforesaid.

One chief feature of this invention resides in the dual cylinder and dual piston arrangement with dual pressure applications thereto in predetermined sequence whereby multiple power effect is obtained.

Another chief feature of this invention resides in the cushioning action obtainable at the ends of the stroke in the relative movement of parts.

A further feature of the invention resides in the automatic lubrication provided when desired.

Still a further feature of the invention resides in its reduction of possible points of failure or faulty operation in one form thereof as herein-after pointed out.

Other objects and features of the invention will be set forth more fully hereinafter in connection with the detailed description to follow.

The full nature of the invention will be understood from the accompanying drawings and the following description and claims:

In the drawings—

Fig. 1 is a central sectional view of one embodiment of the invention including the automatic lubricator, parts being illustrated in the collapsed or fully telescoped position.

Fig. 2 is a similar view of the invention, the lubricator being omitted and the parts illustrated being shown in an intermediate extended position.

Fig. 3 is a view similar to Fig. 2 but with the parts in the fully extended position.

Fig. 4 is a view similar to Figs. 2 and 3 but with parts in a position intermediate between that shown in Figs. 2 and 3, and showing the beginning of the return stroke.

Fig. 5 is a top plan view of the invention illus-

trated in the right half of Figs. 2 to 4 inclusive and a transverse sectional view of said parts and taken in a plane above the larger piston.

Fig. 6 is a view similar to Fig. 3 and of a modified form of the invention.

Fig. 7 is a view similar to Fig. 2 and of a further modified form of the invention.

Figs. 8 and 9 are sectional views of the lubricator shown in Fig. 1 and are taken respectively on lines 8—8 and 9—9 on said figure and in the direction of the arrows.

In Figs. 1 to 4 of the drawings 10 indicates a cylinder head having an outward extension 11 by which one end of the device may be mounted. 15 This head is apertured at 12 for connection to a source of pressure, and in certain forms of the invention this may be directly exposed to the atmosphere.

Secured to head 10 is cylinder 13 to which is 20 suitably secured the opposite cylinder head 14. Herein heads 10 and 14 are clampingly connected together, with the cylinder 13 therebetween by rods 15 and nuts 16, see Fig. 5.

Extending into cylinder 13 and centrally from 25 head 10 is the tapered extension 17. This is coaxially chambered as at 18 and said chamber or bore has restricted communication with the cylinder as by collar 19 which has bore 20 therethrough. Any suitable rigid connection will serve.

30 Slidable in the bore 20 is rod 21 and the bore terminating end thereof in chamber 18 is enlarged as at 22. A spring 23a envelopes the rod 21 and at opposite ends bears upon enlargement or head 22 and collar 19 and normally tends to constrain rod 21 to its retracted position as shown in Figs. 2 and 3.

35 Slidable within cylinder 13 is a piston structure including the body 23 upon which is mounted by annular plate or washer 24 and bolts 25, the 40 "leather" 26 or its equivalent. Extending toward head 10 is the tubular extension 27 of the tubular piston rod 28, the latter immediately adjacent the piston structure including therein slots 29 of predetermined length.

45 When these parts are positioned as in Fig. 1, pressure fluid applied at 12 enters tubular extension 27 since it does not seal upon the frustoconical projection 17. Such pressure entering extension 27 escapes to the other side of the aforesaid piston structure and therefore this constant pressure is simultaneously applied to both sides of the piston structure and same is stabilized in position and located at the lower end of cylinder 13 because the tubular piston rod is subject to 50 a constraint, such as a spring, not shown, which

constantly urges said piston structure toward that end.

The other end of tubular piston rod 28 is closed as at 28a and rigid therewith is portion 30 connected to a member to be moved, such as a garment press head support. The closed end 28a of rod 28 is apertured at 31 and same is adapted to be connected to a pressure supply controlled by a control, cut-off and release valve arrangement not shown. In action pressure fluid, when the valve is open in one position, is applied to the interior of piston rod 28. When the valve is closed, that pressure is held therein. When the valve is moved to another open position, it maintains the pressure supply in cut-off relation and opens the previously pressure supplied interior of rod 28 to the atmosphere.

Such air pressure supply, holding and releasing is conventional to the garment press art, and which also utilizes a return power spring or springs, the spring mentioned hereinbefore and not shown.

The cylinder head 14 herein includes an outwardly projecting portion 32 which includes bore 33 that slidably supports rod 28. For sealing purposes gasket 34 and gland nut 35 or its equivalent may be provided. The bore 33 communicates with cylinder 13 by the conical enlargement 36.

Carried by the upper end of rod 21 and within tubular rod 28 which serves as a cylinder are a pair of opposed piston structures having a predetermined spaced relation. The lower piston structure includes leather 37 and opposed plates 38 and 39, the former bearing upon shoulder 40 of rod 21 near the upper end thereof.

A spacing sleeve 41 at one end bears upon plate 39 and its opposite end bears upon plate 42 of the other piston structure. The latter includes opposed leathers 43 and 44 and upon them bears plate 45. All of the aforesaid is retained upon the rod 21 by the lock washer 46 and nut 47, threaded upon the threaded upper end of said rod.

Included in an offset portion 48, see Fig. 5 as well as Figs. 1 to 4, is a bore 49 having restricted communication with cylinder 13 by port 50, the adjacent end of the bore forming valve seat 51. A valve 52 in bore 49 has a stem 53 slidable in said port and engageable by the large piston near the end of its upward stroke. This unseats the valve and permits cylinder 13 above the large piston to vent to bore 49.

A valve guide and spring retainer is member 54 that slidably supports stem 55 also carried by valve. Concentric with said stem is a spring 56 that has one end bearing upon member 54 and its opposite end bearing upon valve 52. Valve 52 is thus constrained to seated position and piston unseated for venting to the atmosphere. Note that the length of sleeve 41 is sufficient to space the two smaller piston structures at opposite ends of slots 29 in tubular piston rod-cylinder 28 thus sealing off both ends of this cylinder from the ported portion when member 28 is in the position shown in Fig. 3.

Operation

As previously recited, member 28 has been brought back to the position shown in Fig. 1 by a spring power not shown herein and at this time vent valve 52 is held closed by spring 56 and no air pressure, etc., is applied at 31. However, pressure is applied at 12 and is imposed simultaneously on opposite sides of the larger piston.

Application of pressure to intake 31 greater in amount than applied at 12 causes rod-cylinder 28

to elevate. Since slots 29 are exposed, the pressure from 12 is substantially in balance, and the fluid in cylinder 13 readily transfers from one side of the large piston to the other in the elevation of said piston. It will be observed that the initial pressure applied to intake 31 and imposed on the upper small piston lowers rod 21 in opposition to pressure from 12 admitted beneath piston 37 through parts 29. As long as pressure is held or applied to the upper end of the smaller piston structure, same will be held in lowered position provided other forces be not applied or become effective.

When the device is stationary the air pressure at 12 constantly presses against the lower face of piston 37 compressing spring 23a forcing rod 21 upward until member 22 operatively bears against the collar 19 through compressed spring 23a. The rod and spring are maintained in this position until air pressure is admitted at port 31. The pressure from port 31 tends to balance the pressure from intake 12 thereby permitting spring 23a to force rod 21 down until member 22 strikes the bottom of bore 18. The rod and piston structure now remains in this position until the air pressure is exhausted at port 31 at which time this rod and inner piston structure is again forced up by the pressure at intake 12.

At a predetermined part of the upward travel of cylinder 28 the larger piston engages stem 53 of the vent valve 52 to open same. The result is that, since by this time the lower smaller piston has cut off ports 29, pressure from 12 applied to the lower face of the piston is now unopposed or unbalanced so that pressure from 12 becomes effective for raising piston cylinder 28 as the air above the larger piston 23 vents at 50 as the latter elevates. Hence, so far as extension 30 is concerned, it may be said to be first elevated by pressure applied at 31 and then elevated by pressure applied at 12.

Since the large piston is appreciably greater in area than the smaller piston structures, the total force exerted near the end of the relative movement, depending upon what the pressure value is at 12, is quite large. Hence, in this relative movement, as in a garment press, one pressure is first utilized for relative positioning a pressing member, as a head, and then the second pressure can be used for exerting pressing pressure on the buck, or following initial pressing the additional pressure can be utilized for additional pressing pressure as desired. The foregoing is recited merely as illustrative of one type of utilization of this invention.

To release the device, the pressure applied at 31 is released. This results in pressure from 12, applied to the lower face of the lower smaller piston raising piston rod 21 against spring 23a. This changes the blocking or sealing off relationship theretofore existing between cylinder 28 and the smaller pistons, for now ports 29 are exposed to the pressure applied at 12, thus attempting to equalize the pressure at opposite sides of the larger piston so that the larger may be started down by its return spring (not shown) and/or gravity against the action of fluid pressure thereon until vent valve 52 closes. The return spring (not shown) and/or gravity is then relatively unopposed and the larger piston and cylinder 28 then return to the position shown in Fig. 1.

Whenever it is desired to produce a snubbing or cushioning at either end of the stroke, or at both ends, same is accomplished as follows: If the venting at 50 is suitably throttled, the

desired upper snubbing or cushioning action is obtained, dependent upon the degree of throttling imposed. Such additional throttling valve is so obvious, an illustration thereof is intentionally omitted.

Whenever throttling or cushioning at the other end of the stroke is desired, the taper of projection 17 is such as to effect the desired cushioning or snubbing. Obviously each arrangement is never of cut-off type, or otherwise the device will not function as hereinbefore described.

In Fig. 6 there is illustrated a modified form of the invention. Herein the venting of the pressure above the larger piston, instead of being mechanically released by piston vent valve control, is released by exposing vents 80 to atmosphere. These vents are in the cylinder-piston rod 81 and the upper and lower smaller pistons 82 and 83 are appreciably spaced apart by elongated sleeve 84, all being carried by rod 85 as shown.

Positioned between these pistons is suitable absorbent material 86 utilized for retention of any surplus lubricant from exhausting to the atmosphere. It also has a tendency to silence the exhaust.

The operation of this form of the invention is substantially the same as that previously described relative to the form of the invention illustrated in Figs. 1 to 5, except as modified as hereinbefore specified.

In Fig. 7 a more complicated form and further modification of the invention is illustrated. Herein 87 indicates the larger cylinder, 88 the larger piston, 89 the smaller cylinder and piston rod, 90 the smaller piston carried by rod 91, 92 the intake, etc., to the cylinder 89, and 93 the constant pressure intake.

Herein cylinder head 94 includes vent port 95 with which is associated spring closed vent valve 96. This head includes the elongated bore 97 in which cylinder 89 is slidable, the bore being suitably sealed at its outer end as at 98. Communicating with this bore is the lateral passage 99 including valve port 100 leading to the interior of cylinder 89. A valve 101 is normally closed by a spring and opens only when pressure fluid is forced through it from passage 108.

Head 102 includes the constant pressure intake 93, passage 103 terminating in valve seat 104 and lateral passage 105 have port 106 controlled by spring loaded valve 107. Conduit 108 completes the bypass between lateral passages 99 and 105.

Herein piston 88 includes a tapered tubular extension 108a merging with cylinder 89 for cooperation with bore 97 as hereinafter pointed out. Also the lower end of rod 91 mounts valve 109 which is slidable thereon and constrained by spring 110. Fixture 111 carried by head 102 cooperates therewith.

Operation is substantially as previously described except that instead of interior bypassing with slots in the piston rod-cylinder, herein bypassing is externally accomplished by the use of three additional valves. This form of the invention has the disadvantage that extra valves, etc., are required, same introducing possible sources of failure.

When pressure is applied at 92, valve 109 is initially closed, and then piston 88 and cylinder 89 is elevated. As same elevates, pressure above piston 88 increases opening check valve 107 for pressure equalization upon opposite sides of piston 88. This main piston elevation continues

until extension 108a enters bore 97 and seals off same. Valves 107 and 109 being closed and with vent valve 96 open, the pressure in the bypass releases through port 100 and hence the pressure above piston 88 is released.

When this occurs, the pressure on piston 88 from intake 93 becomes effective for further movement of rod cylinder 89 and piston 88 until the end of the stroke. When return movement is desired, pressure at 92 is released and valve 109 opens. This equalizes pressure upon opposite sides of piston 88 and permits the outside constraint to return the piston 88 to its lowered position. When pressure is again applied at 92, valve 109 is closed and piston 88 is elevated initially by said pressure supply until equalizing bypassing is terminated, whereupon, as before, pressure from intake 93 upon piston 88 completes the stroke of rod-cylinder 89.

Reference will now be had to Figs. 1, 8 and 9 wherein an automatic lubricating feature is fully disclosed. Therein 120 indicates a supply pipe from a regulated source of pressure. Pipe 120 is tapped into a head 121 and freely communicates with bore 122 therein. Bore 122 has restricted communication as at 123 with an aligned bore 124 connected to line 125 in turn connected to the constant pressure intake such as intake 12 in Figs. 1 to 4, intake 79 in Fig. 6 and intake 93 in Fig. 7. Leading downwardly from bore 122 is passage 126, see Fig. 1. Depending from the head 121 is projection 127 through which extends the passage 128. This terminates in chamber 129 in said head and said chamber has communication with bore 124 as at 129a. This is controlled by needle valve 130, adjustably carried by said head as at 131 and includes regulating arm 132.

A detachable cup 133 has its upper end engaged with seat 134 on the lower face of the head. A yoke 135 has bearing 136 that engages the lower end of the bowl or cup and screw 137 has threaded engagement with the upper end of said yoke and bears upon the upper face of said head 121 thereby clampingly securing the cup and head together.

This cup is filled to the desired elevation with lubricating oil. The oil is forced up through passage 128 due to the pressure applied to the surface of the oil in the cup.

The needle valve 130 regulates the flow. When closed, no oil is supplied. This oil lubricates the larger piston and cylinder and the smaller cylinder and piston cooperating surfaces.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. A pressure operated device comprising a main cylinder, an annular main piston therein having a hollow piston rod projecting out of one end of the main cylinder, the projecting end of the hollow rod being closed to form a small cylinder, a relatively stationary small piston in the small cylinder, means for selectively controlling the application of fluid under pressure to the small cylinder between its projecting closed end

and the small piston, means for continuously applying fluid under pressure to the main piston at the side thereof opposite the piston rod, a normally open bypass passage for fluid flow between opposite sides of the main piston, a normally closed vent passage for the rod end of the main cylinder, and means responsive to a predetermined movement of the main piston following the admission of fluid under pressure to the small cylinder for opening the vent passage and closing the bypass passage, whereby the pressure at the rod side of the main piston is vented and the pressure at its other side is effective to cause continued movement of the main piston and its connected small cylinder.

2. A pressure operable device as defined by claim 1 wherein there is provided an ejector type operable lubricant supply means, included in the main cylinder continuous pressure applying means, and the small cylinder is provided with vent ports arranged for free discharge when the latter is appreciably projected, the small piston being of dual, axially spaced, piston type, and lubricant trapping means between the small piston spaced portions and adapted for exhaust silencing purposes.

3. A pressure operable device as defined by claim 1 wherein there is provided valve means carried by and responsive to movement of the small piston, movement thereof being responsive to fluid pressure application to the small cylinder.

4. A pressure operable device as defined by

claim 1, wherein the small cylinder includes ports in the main piston end thereof, and small piston controlled to vent the adjacent end of the main cylinder upon predetermined relative movement of the small cylinder with respect to its piston.

5. A device as defined by claim 1 wherein the venting means comprises a normally closed vent valve, and means extending into the main cylinder and operable by the main piston in its movement for opening the valve.

6. A device as defined by claim 1 wherein the smaller cylinder includes a normally opened bypass opening into the main cylinder immediately adjacent the main piston.
